UNITED STATES PATENT OFFICE.

THOMAS MOUNTFORD, OF NEWARK, NEW JERSEY, ASSIGNOR TO BLANCARD & COMPANY, OF NEW YORK, N. Y., A FIRM.

JEWEL-SETTING.

1,032,762.

Specification of Letters Patent. Patented July 16, 1912.

Application filed June 20, 1911. Serial No. 634,215.

To all whom it may concern:

Be it known that I, THOMAS MOUNTFORD, a citizen of the Dominion of Canada, and a resident of Newark, in the county of Essex 5 and State of New Jersey, have invented certain new and useful Improvements in Jewel-Settings, of which the following is a specification.

This invention relates to improvements in 19 jewel settings and the objects of the invention are to provide the inner surfaces of the setting and the sides of the cramps or claws with one kind of metal, whereas the main body of the setting is made of another kind 15 of metal which is exposed on the outer surfaces of the setting and claws.

To the accomplishment of the above objects, and to such others as may hereinafter appear, the invention comprises a setting, 20 the main body and outer surfaces of which are made of one metal, whereas the inner surfaces of the setting, which face the jewel held by the setting, are made of another metal usually a metal which will better set 25 off the jewel held by the setting.

Referring to the drawings: Figure 1 is a side view of a setting constructed in accordance with my invention. Fig. 2 is a plan view of the body blank. Fig. 3 is a plan 30 view of the surface blank. Fig. 4 is an end view of Fig. 2. Fig. 5 is an end view of Fig. 3. Fig. 6 is a plan view of the blanks shown in Figs. 2 and 3 soldered together. Fig. 7 is a side view of the setting which has 35 been pressed from the assembled blanks shown in Fig. 6. Fig. 8 is a plan view of Fig. 7.

In the drawings A designates the body blank which is made of one piece of metal 40 suitably formed to provide claws or cramps B.

C designates the surface blank which is made of one piece of metal suitably formed as shown in Figs. 3 and 5 so as to inclose 45 the body blank A leaving only the top surface of the blank A exposed when the blanks A and C are assembled as clearly shown in Fig. 6. After the blanks A and C have been 50 assembled and suitably soldered together to form a single piece of metal, as shown in Fig. 6, the assembled blank is pressed into the form shown in Figs. 7 and 8, so that the surface blank C will cover the inner surfaces of the setting and the sides of the claws or cramps leaving the body blank ex-

posed on the outer surface of the setting and the outer surface of the claws B as clearly shown in Figs. 7 and 8.

In settings for holding diamonds and similar jewels, the luster of the jewel is 60 greatly enhanced by the use of a suitable background and with this idea in view a great many settings are made entirely of platinum which is a white metal that adds 65 greatly to the brilliancy of the jewel. When the setting is made entirely of platinum it is not only very expensive but the outside 70 of the setting, being white, is not nearly as attractive as a gold setting. To overcome the above difficulties and at the same time 75 to produce a setting which will not only have all of the advantages of a solid platinum setting and a solid gold setting, I have constructed a setting, made as above described, 80 in which the body blank A is made of gold and the surface blank C is made of platinum. The surface blank C is made of rather thin platinum sheets as its only object is to cover the inner surfaces of the setting and the sides of the claws, the body 85 blank A being made of sufficient thickness to afford the necessary strength.

With a setting made, as above described, of platinum and gold, it will be seen that a platinum surface is provided on all of the 85 surfaces of the setting which in any way contribute to reflecting the light upon the jewel, whereas a gold surface is provided on all of the surfaces of the setting which do not contribute to reflecting the light upon 90 the jewel. It is also to be noted that my improved setting is cheaper than a setting made entirely of platinum with many more advantages.

While the invention has been described 95 with particular reference to the detail of construction, the same is not to be considered as limited thereto, as many changes may be made and still fall within the scope of the following claims.

What I claim is:—

1. A jewel setting provided with claws, comprising a body blank of relatively thick metal, and a surface blank of relatively thin metal, said surface blank being arranged to 105 cover the inner surfaces of the body blank and the sides of the claws of said body blank as and for the purposes set forth.

2. A jewel setting provided with claws, comprising a body blank of relatively thick 110

metal, and a surface blank of relatively thin metal, said surface blank being arranged to inclose the body blank leaving only one side of the body blank exposed, as and for the 5 purposes set forth.

3. A jewel setting provided with claws, comprising a body blank of relatively thick metal, and a surface blank of relatively thin metal, the edges of said surface blank being 10 bent and arranged to inclose the body blank

leaving only one side of the body blank exposed, as and for the purposes set forth.

In testimony whereof I have signed this specification in the presence of two subscribing witnesses.

THOMAS MOUNTFORD.
